UNITED STATES PATENT OFFICE.

ELIJAH MCCOY, OF DETROIT, MICHIGAN, ASSIGNOR OF ONE-HALF TO GEORGE W. JONES, OF DETROIT, MICHIGAN, AND ONE-HALF TO C. J. BRONER, OF DETROIT, MICHIGAN.

DESIGN FOR A RUBBER HEEL.

Application filed February 19, 1923. Serial No. 5,211. Term of patent 3½ years.

To all whom it may concern:

Be it known that I, ELIJAH McCoy, a citizen of the United States, residing at Detroit, in the county of Wayne and State of Michigan, have invented a new, original, and ornamental Design for Rubber Heels, of which the following is a specification, reference being had to the accompanying drawing, forming part thereof.

Figure 1 is a plan view of a rubber heel, showing my new design, and Fig. 2 is a perspective view of the same.

I claim:—

The ornamental design for a rubber heel, as shown.

ELIJAH MCCOY.
